Attorney, Agent, or Firm—Evenson, McKeown, Edwards & Lenahan, P.L.L.C.[57] **CLAIM**

The ornamental design for line guide for fishing rod, as shown and described.

DESCRIPTION

FIG. 1 is a perspective view of line guide for fishing rod embodying my new design;

FIG. 2 is a top plan view thereof;

FIG. 3 is a front elevational view, the rear being a mirror image thereof;

FIG. 4 is a bottom plan view thereof;

FIG. 5 is a right side elevational view thereof;

FIG. 6 is a left side elevational view thereof; and,

FIG. 7 is another front elevational view. The broken line showing of part of a fishing rod is for illustrative purposes only and form no part of claimed design.
